UNITED STATES PATENT OFFICE.

LLOYD M. TINGLEY, OF PAWTUCKET, RHODE ISLAND, ASSIGNOR OF ONE-THIRD TO SAMUEL GEE AND ONE-THIRD TO CHARLES A. BENNETT, BOTH OF PROVIDENCE, RHODE ISLAND.

INDICATOR FOR VEHICLES.

No. 904,101.

Specification of Letters Patent.

Patented Nov. 17, 1908.

Application filed January 30, 1906. Serial No. 412,366.

To all whom it may concern:

Be it known that I, LLOYD M. TINGLEY, a citizen of the United States, residing at the city of Pawtucket, in the county of Providence and State of Rhode Island, have invented certain new and useful improvements in Indicators for Vehicles, of which the following is a specification, reference being had therein to the accompanying drawing.

My invention relates to indicators for vehicles and the like, and has for its object to provide a simple and effective device to show by day and adapted to also be illuminated to distinctly show at night both the license number and also indicate the State in which said number is registered, or other medium for identifying the owner of an automobile or carriage, in case of accident or violation of the local laws.

Another feature of my invention is that in addition to showing the number and indicating the State, the device is also adapted to show a red or danger signal at night at the rear of the vehicle, which is a further requirement of the law.

The law now provides that an automobilist shall register his car in each State in which he may be traveling, and that upon coming to the State line he must change his number to coincide with the one under which he is registered in that State. It is also necessary that he should indicate in some manner the State in which the number exhibited is registered. A simple and effective means for representing the State is that each State should be indicated by a distinct and separate color.

To comply with all of the above requirements I have provided a simple and effective device in the form of a casing or lantern to be attached preferably to the rear of an automobile or the like, and have arranged the same in such a manner that the registered numbers of the several States in which I may be traveling, which are indicated on backgrounds of the requisite colors, may be carried therein and readily made interchangeable. For example, under this new law each State will have its own distinct color, for instance, Rhode Island may be black letters upon a white background, Massachusetts white letters upon a blue background, Connecticut black letters upon a red

background, and so forth and so on for the several States, whereby it is only necessary for the authorities to note the color in order to know that the automobile is carrying the proper State number.

The essential feature of my device is that the different numbers and colored plates can be stored in the lantern and easily changed and placed into position upon crossing the line of a State one is about to enter.

With these and other objects in view, the invention consists of certain novel features of construction, as will be more fully described and particularly pointed out in the appended claims.

In the accompanying drawings:

Figure 1—is a perspective view of my improved lantern or indicator. Fig. 2—is a central section through the same. Fig. 3—is an enlarged section showing the arrangement for holding the several plates. Fig. 4—is a perspective view of the lamp. Fig. 5—is a perspective view showing one of the plates as held in its retaining springs. Fig. 6—is an enlarged view showing one end of one of said retaining springs.

Referring to the drawings, 1 represents the body or box portion of the lamp or lantern which may be made in any desired form or size and of any suitable material. An upwardly extending portion 2 is provided on the body of the lantern, the front face of which has an opening covered with a red translucent glass 3, or the like, adapted to display the danger signal at night when the lamps within are lighted. A ventilating hole 4 is provided at the top of the lamp the same being covered by a protecting cap 5.

In order to provide a simple and effective means by which the whole interior of the casing may be exposed I have made the front side of the casing into the form of a frame 6 surrounded by a deep rim 7, in which the glass 19 is set, said frame being hinged at 8 to one side of the body portion. This frame is adapted to close over a lip or ledge 9 on said body portion and be held in that position by engaging a slight projection or protuberance 10 which serves to lock the front frame in its closed position, when the end door (hereinafter described) is open, rendering the whole casing both water and dust tight. The side or end door 11 is hinged at 12 on said frame 6, the opposite edge being

provided with eye strips 13—13 through which the lock pin 14 is adapted to pass to secure the same in position. A small peephole 15 is provided in this door through 5 which the condition of the burning lights may be observed.

An essential feature of my improved device is the simple and effective means by which these plates may be held in their respective positions and also be readily withdrawn from said positions to be replaced with plates of other colors or other numbers. To accomplish this a guide formed of a corrugated plate 16, having longitudinal V-shaped grooves 17 and 18, has been provided and is designed to be supported on the lower rim 7^a of the front casing to receive the lower edges of the plates 19 and 20. At 21 is a spring having two sets of resilient fingers 22 and 23, the ends of each finger being provided with downwardly projecting lips 24 forming a U-shaped portion, see Fig. 6, for receiving the upper edge of the plates 19 and 20. This spring is attached by rivets or other suitable means to the upper rim 7 of the front frame and serves to firmly retain the plates in position and prevent them from rattling.

In order to form a dust-tight case the front or protecting transparent plate of glass 19^a is held in position at its lower edge by means of a spring lip 29 on the lower supporting member and by the spring fingers 23—23 at its upper edge. A duplicate set 35 of springs 25 may be attached to the angle plate 26 at the back portion of the lantern and supporting members 27 are also arranged to receive the lower edge of the extra plates, which are likely to come into use during the trip. Any number of spaces or supporting members may be arranged for storing any desired number of plates.

A lamp 28 may have any desired number of burners, but for convenience three are shown, one of said burners 29 being considerably elevated above the other two for the purpose of illuminating the red or danger signal. This lamp may be held in any desired manner but for convenience the same 50 is preferably provided with lips 30 at either end, adapted to slip under corresponding spring clips (not shown) in the body of the lantern to hold the same firmly in position.

In some cases it is found advisable to have the number represented on one plate which will be transparent, while the color representing the State may be on a second plate. Then by placing one back of the other, as indicated in the drawings, both may be visible through the front of the lantern. In other cases the number may be placed on a plate of the requisite color in which case one plate alone will answer the purpose, but where a man has his same number registered 60 in the several States, then by placing said

number on a separate plate it would be only necessary to change the color plate as he passes from one State to another.

In the practical operation of my device when one is traveling in his automobile and is about to cross the line from one State into another State, where it is necessary to change the number and color of the indicating sign, the pin 14 is withdrawn from the clasps on the door, which is then swung open 75 on its hinge 12, and if it is desired to remove or inspect the lamps or any part of the interior of the body portion the whole front frame may be swung open on the hinge 8 at the opposite side thereof forming a ready access to the whole interior. The lamp may be lighted, if night is coming on, and the plates changed from the back to the front of the lantern with but a moment's delay.

The device is extremely simple in construction and efficient in its practical operation and by its use the registered number together with the color indicating the State may be exhibited in such a manner that it is readily discernible by day and also adapted 80 to show clear and distinct by night, the lantern also comprising the combination of a separate and distinct danger signal.

This simple and effective indicator greatly facilitates the work of the local authorities 95 to determine at a glance the number of the vehicle and that it is registered in the State where he is traveling even though the same be passing the observer at a very high rate of speed.

Having thus described my invention what I claim as new and desire to secure by Letters Patent, is:

1. An indicator of the character described comprising a casing adapted to contain an illuminating medium, a guide adapted to receive one edge of a slidable indicating plate, and a friction device provided with guide fingers for engaging the opposite edge of said plate.

2. An indicator of the character described comprising a casing adapted to contain an illuminating medium, a pivoted frame carried by said casing, a guide carried by said frame, an indicating plate slidably mounted 105 in said guide, and a friction device also carried by said frame and engaging the opposite edge of said plate.

3. An indicator of the character described comprising a casing adapted to contain an 110 illuminating medium, a guide adapted to receive one edge of a slidable indicating plate, a friction device provided with guide fingers for engaging the opposite edge of said plate, and means located adjacent the 115 back of said casing for storing a plurality of additional indicating plates.

4. An indicator of the character described comprising a casing adapted to contain an illuminating medium, a guide adapted to re- 120

ceive one edge of a slidable indicating plate, and a friction device provided with resilient fingers for engaging the opposite edge of said plate.

5. An indicator of the character described comprising a casing adapted to contain an illuminating medium, a guide adapted to receive one edge of a slidable indicating plate, and a friction device provided with resilient fingers for engaging the opposite edge of said plate, said fingers having flanges for embracing the sides of said plate.

10. An indicator of the character described comprising a casing adapted to contain an illuminating medium, a front frame pivoted to said casing, a guide carried by said frame, adapted to receive an indicating plate, a friction device also carried by said frame for engaging one edge of said plate, and a pivoted end door also carried by said frame.

15. An indicator of the character described comprising a casing adapted to contain an illuminating medium, said casing being provided with an upper extension, a permanent signal plate carried by said extension, a front frame pivoted to said casing, a guide carried by said frame adapted to receive a slidable signal plate, and a frictional device also carried by said frame for engaging one edge of said plate.

20. An indicator of the character described

comprising a casing adapted to contain an illuminating medium, a plurality of guides each adapted to receive one edge of a slid-
able indicating plate, and a friction device 35 comprising a plate provided with a plurality of guides arranged in pairs, each pair being adapted to engage one edge of each of said plates.

25. An indicator of the character described comprising a casing adapted to contain an illuminating medium, a plurality of guides each adapted to receive one edge of a slid-
able indicating plate, and a friction device comprising a plate provided with a plurality 45 of resilient fingers arranged in pairs and co-
operating with said guides.

30. An indicator of the character described comprising a casing adapted to contain an illuminating medium, a plurality of guides 50 each adapted to receive one edge of a slid-
able indicating plate, and a friction device comprising a plate provided with a plurality of resilient fingers coöperating with said guides, said fingers being each provided with 55 guide flanges.

In testimony whereof I affix my signature in presence of two witnesses.

LLOYD M. TINGLEY.
